UNITED STATES PATENT OFFICE.

FRANK BIANCHI, OF UNION CITY, NEW JERSEY, ASSIGNOR TO SCHWARZENBACH-HUBER CO., OF UNION CITY, NEW JERSEY, A CORPORATION OF NEW JERSEY.

STRIPPER GUIDE.

Application filed March 2, 1926. Serial No. 91,802.

This invention relates to stripper guides used in rewinding silk and has for an object to provide an improved construction wherein the thread is properly guided and at the same time properly cleaned.

Another object of the invention is to provide an improved thread guide wherein the cleaning plate is so arranged that it will not accidentally move out of its support. A further object of the invention is to provide a thread guide wherein the cleaning plate and the holder therefor are so arranged that the plate may be cleaned from time to time without removal.

In the accompanying drawing—

Figure 1 is a fragmentary sectional view through a rail and through a thread guide, disclosing an embodiment of the invention.

Figure 2 is a front view of the guide shown in Figure 1.

Figure 3 is a longitudinal sectional view through Figure 4 on line 3—3.

Figure 4 is a top plan view of the guide shown in Figure 2.

In using silk threads, it is necessary to wind the same on spools or other supports and in doing so the thread is run through a guide which acts in the double capacity of a guide and cleaner for removing knots, ravelings and foreign matter. Usually the thread has been previously subjected to an oiling operation so that these different materials may be removed without breaking the thread and by reason of the cleaning action, the thread on the spool or other member will be properly sized and free of enlargements so that the cloth woven therefrom will likewise be free of objectionable enlargements.

Heretofore, guides in cleaning devices have been provided, as for instance, the construction shown in my prior Patent No. 1,526,954. As shown in my prior patent and also in other structures, a guide and cleaner is provided but when the cleaning plate is to be removed, as for instance, from my prior patent, the machine must be stopped and the thread lifted and then the plate removed, cleaned and returned. This must be done with all of the plates. This action results in a considerable loss of time by reason of the stoppage of the machine while one or more of the plates are cleaned. In the present invention, a guiding and cleaning plate has been provided wherein the accumulated ravelings and other matter may be removed

from time to time without removing the plate and without stopping the machine.

In the accompanying drawing, 1 indicates a guide rail in which the thread guide 2 is mounted. The thread guide 2 is provided with a cleaning plate 3 which acts to clean and in a certain sense size the thread 4 passing therethrough. The thread 4 is supplied from a suitable reel 5 which is preferably comparatively large and after the thread has passed through the guide, it is wound on a suitable spool 6. It is, of course, understood that the reel 5, spool 6 and also the rail 1 form no part of the present invention but have been shown to clearly illustrate the function of the various parts of the guide.

Preferably, the guide 2 is made of vitreous material and is formed with a pair of notches 7 and 8 which merge into rounded sections 9 which in turn merge into the upper part of the guide. In addition to the notches 7 and 8, the guide is provided with aligned holes 10 and 11 and with a groove 12 at the top, said groove being adapted to receive the usual springs which hold the guide in place, on the rail 1. The guide 2 is provided with an opening or socket 13 having offset portions for presenting shoulders 14 and 15 as shown in Figure 3. This arrangement of socket permits the use of the plate 3 which is provided with extending lugs or shoulders 16 and 17, said shoulders being adapted to fit against the shoulders 14 and 15 whereby the aperture 18 in plate 3 is held in alignment with the apertures or holes 10 and 11. A narrow opening 19 extends from the aperture 18 to the upper end of the plate 3 and determines the thickness of thread passing through the plate. It will be noted from Figure 3 that the plate 3 is also provided with inclined upper portions 20 and 21 which properly guide the thread into the slit or opening 19 when the thread is first being placed in position. The depth of the notches 7 and 8 in the guide 2 causes the thread to pass substantially centrally through the slit or opening 19, that is, the thread passes through the plate 3 about half way from the aperture 18 to the top of the plate.

In actual operation, the thread may move up and down slightly but any ravelings or other foreign matter is scraped therefrom and is gradually forced downwardly into the aperture 18 from which it may be readily

removed through either of the openings 10 or 11. In this way, accumulated foreign matter may be removed from the plate 3 at any time and if necessary, without stopping the machine. The machine may be operated at a maximum speed without danger of the plate 3 jumping out of the guide as the plate is held by the shoulders 16 and 17.

What I claim is:—

- 16 1. A stripper guide comprising a body formed with a socket having offset portions at one end whereby shoulders are formed on the body, and a stripping and guiding plate having members acting as shoulders co-act-

ing with the first mentioned shoulders for 15 preventing movement of said plate longitudinally of said socket in one direction.

2. A stripper guide comprising a body formed with a socket extending entirely through the body and substantially flaring at 20 the bottom portion, and a cleaning and guiding plate mounted in said socket and formed with extensions, said extensions engaging the body at the flaring portion whereby when the guide is in use the plate cannot be removed. 25

FRANK BIANCHI.
